UNITED STATES PATENT OFFICE.

ALVIN POND, OF MARION, CONNECTICUT.

DIE FOR HEADING BOLTS.

SPECIFICATION forming part of Letters Patent No. 243,967, dated July 5, 1881.

Application filed April 11, 1881. (No model.)

To all whom it may concern:

Be it known that I, ALVIN POND, of Marion, in the county of Hartford and State of Connecticut, have invented a new Improvement in Dies for Heading Bolts; and I do hereby declare the following, when taken in connection with the accompanying drawings and the letters of reference marked thereon, to be a full, clear, and exact description of the same, and 5 which said drawings constitute part of this specification, and represent, in—

Figure 1, a vertical central section of the three dies; Fig. 2, a top view of lower die; Fig. 3, the blank after first operation; Fig. 4, 15 the blank after second operation; Fig. 5, the blank finished.

This invention relates to an improvement in dies for forging bolts of that class in which the head is square. Usually square-headed bolts 20 are made by upsetting, and at the same time striking transversely to form the sides.

The object of this invention is to shape the bolt complete in the simple operation of upsetting, whereby the mechanism usually required 25 for the transverse striking is avoided; and the invention consists in the series of dies herein-after described, and as shown in the accompanying illustration.

A represents the lower or stationary die, in 30 which are three cavities, B C D, each corresponding in shape to the cylindrical body of the bolt, except at the face or anvil end of the die. The die A is in two parts and arranged to gripe upon the body of the blank, so as to 35 hold it firmly against the upsetting force in the usual manner for heading bolts. At the face end of the die the first cavity, B, is countersunk, so as to form an outwardly-inclined enlargement, as at a. The second cavity, C, 40 has a like countersink, but slightly larger. The third and finishing cavity has a recess, d, cut at the anvil end corresponding to the four sides of the head, and in depth sufficient to inclose the four sides of the entire finished head, and 45 so as to leave a square shoulder at its junction with the cylindrical part of the cavity D. The other or movable part of the die E has a cavity, F, in line with the cavity B, in the shape of a frustum of a cone, its outer or larger end 50 corresponding in diameter with the countersink a in the part B. It is also constructed

with a second cavity, G, in line with the second cavity, C, in the other part, its outer diameter corresponding to the countersink b in the other part—that is, somewhat larger than the largest diameter of the cavity F, but less in depth, and said cavity may be in the form of a frustum of a cone—but preferably the side walls are curved from the outer end inward. 55

The blank is introduced into the part A in 60 the usual manner, projecting therefrom sufficiently to fill the cavity F in the part E, and also the countersink a in the part A. The part E is then forced upon the blank, upsetting the end, so as to fill the cavity F and countersink, 65 as seen in Fig. 3. It is then transferred to the second cavity, C, with the shoulder f resting in the countersink. Then the part E is forced on the projecting end, which upsets the blank, as seen in Fig. 4, leaving the same incline underneath the enlarged part. It is then transferred into the third cavity, D, with its shoulder f resting on the shoulder e of the cavity. 70 The two parts of the die are brought together to close upon the body of the blank which compresses the sides of the enlarged part of the blank in the cavity D, and reduces it to the shape of the cavity—that is, four square sides. Because of the tapering shape of the enlargement the head comes square in the lower part 75 of the die and leaves the corners rounded, as seen in Fig. 5—the usual and desirable shape for this class of bolts. After thus shaping by side compression the follower is brought down on the head to flatten its face. 80

By this construction no trimming of the head is necessary. It is positively central, and, because of the inclined under side of the enlargement made by the countersinks in the first and second cavities, there is no liability to “cold-shuts,” flaws, or breaks at the junction of the head with the body. 85

The first cavity may in some cases be dispensed with, and the upsetting and enlargement formed in the second cavity alone; but 90 in larger bolts the two preparatory operations produce the best results.

The parts of the die which perform the first and second operations—that is, the first and second cavities—are substantially the same as 95 that for which Letters Patent were granted to myself and Frost April 12, 1881. I therefore 100

do not claim dies having those cavities, except in combination with the peculiar third or finishing cavity.

I claim—

- 5 The herein-described dies for making square-headed bolts, consisting of the lower part, A, made in two parts, constructed with a cavity, C, corresponding to the body of the blank, and so as to grasp the same, countersunk at its face 10 end b, and also with a cavity, D, of the shape of the body of the blank, with a recess, d, at its face end corresponding to the square head shape to be produced, the division in this part A being longitudinally central through

said cavities, combined with an upper or second part, E, constructed with a cavity, G, of substantially frustum-of-a-cone shape, in line with the before-mentioned cavity C in the part A, the face of said second part, E, adjacent to the second cavity D in the part A being flat, and so that the blank upset in the cavity G will be squared in the cavity D when the two parts of A are closed upon the blank, substantially as described. 15 20

ALVIN POND.
